HOUSING FOR PULLING MECHANISM

Joseph B. Ulicny, 414 Littel Ave., Dayton, Ohio 45409

Filed July 24, 1967, Ser. No. 7,961

Term of patent 14 years

(Cl. D41—1)

FIGURE 1 is a perspective view of a housing for pulling mechanism showing my new design, the broken lines are for illustrative purposes only.

FIGURE 2 is a top view thereof.

FIGURE 3 is a bottom view thereof.

FIGURE 4 is a side view, taken from the lower side of FIGURE 2.

FIGURE 5 is an end view, taken from the right hand end of FIGURE 4.

FIGURE 6 is a side view, taken from the upper side of FIGURE 2.

FIGURE 7 is an end view taken from the right hand end of FIGURE 6.

I claim:

The ornamental design for a housing for pulling mechanism, substantially as shown and described.
